ALBERT CARTER, OF NEW YORK, N. Y., ASSIGNOR TO HIMSELF
AND GEORGE K. RYAN, OF SAME PLACE.

Letters Patent No. 90,922, dated June 8, 1869.

IMPROVED CORD-TIGHTENER FOR CURTAIN-FIXTURES.

The Schedule referred to in these Letters Patent and making part of the same.

To all whom it may concern:

Be it known that I, ALBERT CARTER, of the city and State of New York, have invented, made, and applied to use, a new and useful Improvement in Cord-Tighteners for Curtain-Fixtures; and I do hereby declare the following to be a full, clear, and exact description of the said invention, reference being had to the annexed drawing, making part of this specification, wherein—

Figure 1 is an elevation of said cord-tightener; and Figure 2 is a partial section of the same, vertically. Similar parts are denoted by the same letters.

This invention is to furnish a cheap and reliable means for tightening the cords of curtain-fixtures; and consists in a strap, of flexible material, passing through a clamping-buckle, that carries a grooved segment, or wheel, around which the cord passes.

This device allows the endless cord to be tightened or slackened with great facility, and the friction of the endless cord, in passing around the grooved segment, or wheel, prevents the curtain running down by its own weight.

In the drawing—

a is a segment, or a wheel with a grooved edge, for the cord *b* to pass around.

This segment is attached firmly to the frame *c*, that

is provided with a cross-piece, *d*, around which the strap *e* passes, and is firmly attached to the window-casing, or other point of attachment, by the screw, or nail *f*.

The strap *e*, passing around the cross-piece *d*, is clamped, said cross-piece *d*, in connection with the frame *c*, forming a clamping-buckle, so that the strap *e* can be tightened up, as occasion may require, and, if necessary, it may be loosened, thereby greatly facilitating the adjustment of the tension of the curtain-cord, and, at the same time, the strap can be of ornamental woven material, so that the appearance of the fixture is much better than the usual brass slide.

What I claim, and desire to secure by Letters Patent, is—

Clamping-buckle, formed by the cross-piece *d* and frame *c*, in combination with the grooved segment, or wheel *a*, and the adjusting-strap, as and for the purposes set forth.

In witness whereof, I have hereunto set my signature, this 5th day of April, 1869.

ALBERT CARTER.
